UNITED STATES PATENT OFFICE.

ANDREW J. SANFORD, OF NEWARK, OHIO, ASSIGNOR TO A. H. HEISEY & CO., OF NEWARK, OHIO.

DESIGN FOR A BOWL OR SIMILAR ARTICLE.

Application filed February 8, 1921. Serial No. 443,474. Term of patent 14 years.

To all whom it may concern:

Be it known that I, ANDREW J. SANFORD, a citizen of the United States, residing at Newark, Ohio, have invented a new, original, and ornamental Design for a Bowl or Similar Article, of which the following is a specification.

In the drawings:—

subject matter of the invention physically embodied as a mayonnaise dish.

Figure 2 is a top plan view of the article shown in Figure 1.

I claim:—

The ornamental design for a bowl or similar article, substantially as shown.

ANDREW J. SANFORD.
